UNITED STATES PATENT OFFICE.

OTTO E. ENELL, OF WABASH, INDIANA, ASSIGNOR TO HIMSELF AND
WILLIAM S. STITT, OF SAME PLACE.

COMBINATION SHADE, CURTAIN, AND LAMBREQUIN SUPPORTER.

SPECIFICATION forming part of Letters Patent No. 349,635, dated September 21, 1886.

Application filed January 26, 1886. Serial No. 189,812. (No model.)

To all whom it may concern:

Be it known that I, OTTO E. ENELL, of Wabash, in the county of Wabash and State of Indiana, have invented certain new and useful Improvements in Combination Shade, Curtain, and Lambrequin Supporters; and I do hereby declare that the following is a full, clear, and exact description of the invention, which will enable others skilled in the art to 5 to which it appertains to make and use the same, reference being had to the accompanying drawings, and to the letters of reference marked thereon, which form part of this specification.

My invention relates to devices for supporting 15 shades, curtains, lambrequins, &c., at windows, doorways, alcoves, &c., and has for its object to furnish a single complete device which shall act as a support for either, any, or all of them, and shall be cheap and simple 20 to make, easily adjusted to position or removed therefrom, handsome in appearance, and not liable to get out of order.

With these ends in view my invention consists in the improved construction, arrangement, and combination of parts, which I shall 25 now proceed to fully describe, and afterward specifically point out in the claims hereto appended.

Figure 1 is a perspective view of my device 30 in its operative position, showing the manner of suspending from it a shade, a lambrequin, and a curtain. Fig. 2 is a view of a central portion of the supporter, showing the manner of supporting and adjusting it at its center. Fig. 3 is a view of the central supporting bracket in side elevation, also showing the 35 adjusting-tube. Fig. 4 is a view in top plan of one-half of the main supporting device detached; and Fig. 5 is a view in end elevation 40 of the supporter in place, as in Fig. 1, the curtain and lambrequin being omitted.

Like letters of reference mark the same parts in all the figures.

Referring to the drawings by letters, A represents the frame or upper facing of a window or similar opening, into which are secured the staples or screw-eyes a a' a'' , the last being centrally located and the first two near the ends of said facing.

50 My supporter consists of two pieces of wire, B B', bent to the shape as follows: Beginning

at the two outer ends b b' are downward-projecting ends which fit into the eyebolts a a' and serve as end supports. From the upper ends of these parts b b' the wires continue horizontally outward at c c' , thence downward at d d' , curving outward at e e' and upward at f f' , forming U-shaped supports for the journal of the shade-roller. At the top of these supports the wire continues horizontally inward at g g' to the facing A, thence along the facing outward at h h' for a short distance, thence in semicircular curves at i i' until again parallel with the facing and the parts h h' , and continuing in said parallel positions, as at j j' , to 65 and into the central tube, C, which is centrally supported on a bracket, D. This bracket consists of two arms, D' D'', and a ring or other suitable construction, d'', at the inner end of the upper one of them, which engages the 70 staple or eyebolt a'' in casing A.

E is a shade mounted on a roller, as is usual, upon the ends of which are journals E', which, as before stated, are supported in the U-shaped bends of the supporter. These shades and 75 rollers may be of any ordinary or approved construction, spring-rollers being preferred, for the reason that with them no other fixture is necessary, the oblong end e'' of such roller fits between the upright pieces d d' of the 80 U-shaped supports, and is thereby kept from turning with the roller. Such fixtures usually have one square or oblong journal or pintle and one round one, the latter being secured rigidly to turn with the roller, and the former 85 being attached to one end of the spring whose opposite end is secured to the roller, the object being to coil and uncoil the spring by turning the roller, and thus wind up the shade. The central or inner ends of the two wires B 90 B', as before stated, enter the central tube, C, which tube is supported by the central bracket, D, the wire of which passes through the said tube, holding it in a rigid position, the upper wire being hung in the eyebolt a'' , the 95 lower acting as a stiffening brace or support when weight is placed upon the supporter, thus taking much of the strain off the eyebolts a a' .

F represents a lambrequin, and G a curtain. 100 Either or both of these may be secured to the supporter by passing the wires through a hem,

as at F', or by means of rings, as is well known. This whole structure presents a light and neat appearance when in use, and may be made of wire or any other suitable material. A cornice may or may not be used with it, according to the taste of the user, and while the device is very cheap to construct and simple to operate it is durable and ornamental.

When it is not desired to have the supporter 10 adjustable to different widths of shades or windows, the wires B B' may be made in one single piece, and the central tube in that case may be displaced by a ring made in the apex of the bracket D.

15 As now constructed in two pieces the width between the U-supports may be regulated by simply moving the staples or eyebolts a a' nearer to or farther from each other to suit different widths of windows or shades, the 20 limit of such adjustment being the length of the central tube.

Having thus fully described my invention, what I claim, and desire to secure by Letters Patent, is—

25 1. A supporter having U-shaped supports for a shade-roller, an outward bend at each

end, a curtain or lambrequin holder parallel to the window-facing, and bent ends to engage with eyebolts or staples in said facing, as set forth.

2. A combined shade, curtain, and lambrequin supporter, consisting of wire or similar material having ends b b' to engage eyebolts or staples in the facing, U-shaped supports for a shade-roller, outward-bent semicircular 35 ends, and front pieces parallel with the facing, in combination with a central tube to receive said ends and a bracket for supporting said tube, as set forth.

3. In combination, the wires B B', bent, as 40 described, to form shade-roller supports, attaching ends, and front pieces, j j', with the bracket D, having end or ring to engage eyebolt a'', arms D' D'', and central tube, C, to receive ends j j', as set forth.

In testimony that I claim the foregoing as my own I hereto affix my signature in presence of two witnesses.

OTTO E. ENELL.
